UNITED STATES PATENT OFFICE.

ALEXANDER J. KALINOWSKI, OF LYONS, COLORADO.

MULTIPLE-FUSE PLUG.

1,103,777.

Specification of Letters Patent.

Patented July 14, 1914.

Application filed July 18, 1913. Serial No. 779,836.

To all whom it may concern:

Be it known that I, ALEXANDER J. KALINOWSKI, a citizen of the United States, residing at Lyons, in the county of Boulder 5 and State of Colorado, have invented new and useful Improvements in Multiple-Fuse Plugs, of which the following is a specification.

This invention relates to improvements 10 in multiple fuse plugs.

In carrying out the present invention, it is my purpose to provide a multiple fuse plug wherein the fusible elements may be brought into service singly and one after 15 the other as the same become burnt out or otherwise mutilated and wherein the component parts will be so correlated and arranged as to reduce the possibility of derangement to a minimum and enable the 20 plug to be readily disassembled so that the fusible elements may be renewed when occasion demands.

It is also my purpose to provide a multiple fuse plug which will embrace the desired 25 features of simplicity, efficiency and durability, one which may be manufactured and marketed at a minimum expense and one which may be readily installed in and renewed from an electric circuit.

30 With the above and other objects in view, the invention consists in the construction, combination and arrangement of parts hereinafter set forth in and falling within the scope of the claims.

35 In the accompanying drawing; Figure 1 is a view in elevation of a multiple fuse plug constructed in accordance with my present invention. Fig. 2 is a vertical sectional view through the plug. Fig. 3 is a 40 cross sectional view therethrough.

Referring now to the accompanying drawing in detail, the numeral 1 designates the body of the plug, such body being constructed of porcelain or other suitable insulating material and formed with a longitudinal bore 2 opening onto one end thereof and provided with a centrally disposed partition 3 by means of which the bore 2 is divided into independent chambers or 45 compartments. Formed in the closed end of the bore 2 approximately centrally thereof is an opening in which is mounted a bushing 4 receiving a contact screw 5, and at opposite sides of the central opening in 50 the partition 3 are passages 6, 6 leading into

the respective chambers or compartments. In the present instance, the outer wall of the body at a point approximately centrally of its length is circumferentially reduced and has such reduced portion tapered or beveled inwardly as at 7 for a suitable distance, the remaining part of such circumferentially reduced portion being of uniform diameter as at 8. The tapering portion of the outer wall of the body is formed with a number of transverse grooves 9, two being shown in this instance and disposed at diametrically opposite points and each groove adjacent to one end thereof opens into a recess 10 formed in the body, while the opposite end communicates with one of the chambers formed by the partition 3 by way of an aperture 11. Disposed within each chamber or compartment formed by the partition 3 and the adjacent portion of the wall of the bore 2 is a fusible element 12 having one end thereof passed through the respective passage 6 and secured to the contact screw 5 and the opposite end thereof passed through the aperture 11 and lying 55 upon the lower wall of the respective groove 9 and bent upon itself and extended into the recess 10 contiguous such groove. Thus, it will be seen that the outer portion of the fusible elements 12, lying within the grooves 9, 9 are disposed in a plane below that of the outer wall of the body 1.

Surrounding the outer wall of the body 1 and of a configuration conforming to the contour thereof is a shell 13 preferably formed of brass and having the relatively large end thereof formed to provide shells 14 adapted to engage the socket with which the plug co-operates. The portion of the shell 13 between the large and small ends 60 thereof, that is the part of the shell corresponding to the portion 7 of the outer wall of the body 1 is stamped or cut out to provide an inwardly projecting contact strip 15 adapted to aline with one or the other of the grooves 9 and engage the adjacent portion of the respective fusible element so that the shell and contact screw will complete the circuit, as is well known. Surrounding the relatively small end of the body 1 and the like end of the shell 13 is a cap 16 constructed of porcelain or other analogous material and having one end of the bore thereof diverging outwardly as at 65 17 so as to overlie the intermediate portions 110

of the shell and body. Thus, the plug, when the constituent parts thereof are assembled, is given a substantially uniform shape.

From the foregoing description taken in connection with the accompanying drawing, the construction, mode of operation and manner of employing my invention will be readily apparent. Assuming the parts to be assembled as illustrated in Fig. 2 and connected in the electric circuit, it will be seen that the circuit is established through the contact screw 5, the portion of the shell 13 within the socket and the fusible element 12 in engagement with the contact strip 15 on the shell, the other fuse being cut out of the circuit incident to the exposed portion thereof lying in a plane below that of the shell. Should the active fuse become burnt out or otherwise mutilated, it is only necessary to remove the cap 16 to withdraw the body a slight distance from the shell and rotate such body so that the groove 9 carrying the respective end of the remaining fuse will be brought into registration with the strip 15, the body being now forced into the shell whereby the strip 15 on the shell is engaged with the adjacent portion of the fusible element.

It will be seen that I have provided a multiple fuse plug whereby the fusible elements may be placed in circuit successively as the same become burnt out or mutilated and wherein such elements may be readily renewed or replaced.

While I have herein shown and described one preferred form of my invention by way of illustration, I desire to have it understood that I do not limit or confine myself to the precise details of construction herein described and delineated, as modification and variation may be made within the scope of the claims without departing from the spirit of the invention. Furthermore, I wish it to be understood that the capacity of the plug may be increased and such is contemplated.

I claim:

1. A fuse plug comprising a body, a contact carried by said body, fusible elements each having one end secured to said contact and the opposite end in engagement with the

outer surface of the body, a shell surrounding said body, a strip stamped from said shell and in engagement with the outer end of one of said elements and capable of engaging the outer end of the remaining element, and a cap for said body.

2. A fuse plug comprising a body, a contact carried by said body, fusible elements each having one end secured to said contact and the opposite end in engagement with the outer surface of the body, a shell surrounding said body, a strip stamped from said shell and in engagement with the outer end of one of said elements and capable of engaging the outer end of the remaining element, a cap for said body, and a connection between said cap and shell.

3. A fuse plug comprising a body having the outer wall thereof circumferentially reduced and the reduced part tapered for a portion of its length and of a uniform diameter for the remaining portion of its length, the tapered portion being formed with grooves, said body being further formed with a longitudinal bore having a closed end formed with a center opening and passages at opposite sides of such opening, a partition within the bore and dividing the same into chambers or compartments, fusible elements each disposed within one of said chambers and having one end thereof passed through one of said passages and the opposite end passed through the wall of the bore and lying within one of said grooves in the tapered portion of the outer wall of the body, a contact screw disposed within the central opening and connected to the adjacent ends of said fusible elements, a shell surrounding said body and having a finger stamped therefrom and adapted to engage one or the other of the grooves in the tapered portion of the outer wall of the body to place the respective fusible element in the circuit, and a cap for said body.

In testimony whereof I affix my signature in presence of two witnesses.

ALEXANDER J. KALINOWSKI.
